UNITED STATES PATENT OFFICE

157,779

HAIR DRIER

Joseph H. O'Connor, Detroit, Mich.

Application August 23, 1949, Serial No. 4,660

Term of patent 14 years

(Cl. D86—10)

To all whom it may concern:

Be it known that I, Joseph H. O'Connor, a citizen of the United States, residing at Detroit, in the county of Wayne and State of Michigan, have invented a new, original, and ornamental Design for a Hair Drier, of which the following is a specification, reference being had to the accompanying drawing, forming a part thereof, in which:

Fig. 1 is a top plan view of a hair drier, showing my new design;

Fig. 2 is a front elevational view; and

Fig. 3 is a side elevational view.

I claim:

The ornamental design for a hair drier, substantially as shown.

JOSEPH H. O'CONNOR.
